Attorney

UNITED STATES PATENT OFFICE

ROSCO O. PENCE, OF STERLING, KANSAS

CHECK VALVE DAMPER FOR BROODER STOVES

Application filed February 8, 1930. Serial No. 426,976.

This invention relates to brooder stoves and particularly to a thermostatically operated check valve therefor. The general object of the invention is to provide an improved check valve damper which is so constructed and mounted that the damper swings inward in order to open the check draft and when it is swung inward, it extends inward and downward so as to cause the air entering the check draft opening to be directed downward directly against the heated air escaping from the stove causing a turning back of the heated air.

A further object is to so construct the damper that as it is swung inward, it reduces the effective area of the flue opening, thus giving added checking effect; this damper, however, when it is swung to its inoperative position forming no obstruction to the passage of the products of combustion through the flue.

A further object is to so form a damper that it will swing by gravity to its closed position, but when the damper is swung to an open position it is balanced, thus making the damper very readily operable by a thermostatic means.

Other objects will appear in the course of the following description.

My invention is illustrated in the accompanying drawings, wherein:—

Figure 1 is a fragmentary vertical section of a brooder stove showing a check draft damper constructed in accordance with my invention and the operating means therefor;

Figure 2 is a fragmentary section on the same plane as Figure 1, but showing the check draft damper open.

In the drawings I have illustrated only so much of the brooder stove as is necessary to illustrate my invention. In the drawings, 10 designates the body of the brooder stove which is constructed in general accordance with my application, Serial No. 426,975, filed 45 on the 8th day of February, 1930. The brooder stove is formed to provide the magazine 11, and a flue 12 which extends up along the magazine from the fire pot.

This flue is formed to provide a check draft opening 13 formed with a seat 14 at the lower

end and at the sides of the opening and a seat 16 at the top of the opening, the seat 16 facing outward, while the seat 14 faces inward. Pivoted in any suitable manner as upon ears projecting from the body of the stove is the check draft damper 17. This is formed to provide a flat plate-like portion 18 and an angular portion 19 at the upper end of the plate-like portion which angular portion is thickened as it extends away from the plane 80 of the plate 18 and has a flat face which engages against the seat 16. The damper is pivoted by a pivot pin or equivalent element 20 which extends through the damper at the junction of the portion 19 with the plate-like portion 18. The plate-like portion 18 at its upper end adjacent the pivot is formed with the outwardly projecting ear 21 to which a rod 22 operatively connected to any suitable thermostatically operated member is hinged. 70 This rod 22 is preferably formed with a hook at its upper end to engage over a pin 23 on the damper, but I do not wish to be limited to this.

I have illustrated the rod 22 as being connected to a lever 24, this lever in turn being connected to a rod 25 which passes down through a direct draft damper 26, the rod carrying a nut 27. The lever 24 is provided at its inner end with an eye engaging the rods 22 and 25 and at its outer end, this lever is upwardly bent and fulcrumed upon a support 28. Thermostatic bulbs 29 engage the lever so that when the bulbs expand, the inner end of the lever will be forced downward, closing the draft damper 26 and opening the check draft damper 17 and when they contract, the reverse action takes place.

With this construction, when the thermostat expands under the action of heat, the lever 24 is rocked so as to lower the rod 25 and thus close the draft damper and this movement of the lever at the same time acts to pull downward on the rod 22, thus swinging the check draft damper inward and upward to the position shown in Figure 2. If the damper is moved beyond this position, air will enter above the balancing weight 19 which forms part of the damper proper and also below the weight and this air is directed 100

downwardly against the fire. As the damper moves more and more toward a horizontal position, it will more and more cut off the passage through the flue 12 so that it checks the fire not only by cutting off the draft through the flue 12 but by positively directing cool air downward on to the upper face of the fire.

The portion 19 of the check draft damper is, as shown, made thicker and heavier toward the inner end of this portion away from the pivot of the damper. Weight added at this point tends to press the lower part of the damper firmly against the opening and at the same time acts as a balance. This is necessary because the weight of the draw bar, draw wire and of the thermostat, if the latter rests on the draw bar will act to draw downward on the arm which extends downward from the damper. Under these circumstances with the damper nearly vertical, that is, in closed position, it is necessary to use a counter-weight in such a position as to overcome the weight of the parts mentioned above and to urge the lower end of the damper to a closed position. The counter-weight portion 19 in my construction is just sufficiently heavy so that it will securely close the damper and not heavy enough to make any unnecessary weight to lift. With the lower end of the damper hanging nearly vertical, the damper would cause scarcely any pull whatever on the draw wire until the damper had been lifted ten or twelve degrees from the closed position. At this point the damper is exerting its greatest force on the pull wire 22, but at this time the counter-weight is shifted rearward and will have travelled sufficiently far outward as to practically counterbalance the downward pressure at the other end of the damper. Thus at the time the damper is in a horizontal position, it is so balanced that the movement of the thermostat will readily control the damper. If the damper were shifted very much beyond the horizontal, the counter-weight would overbalance the damper and hold it in an open position, but this is made impossible by the angle at which the extended arm is attached to the damper and furthermore the damper is never raised to greater than a horizontal position. While the counter-weight tends to counterbalance the leverage of the damper as it is shifted into a horizontal position, the damper is yet at all times urged by its weight to a closed position.

With this construction, the air entering the check draft opening when the damper is lifted is directed downward toward the lower end of the damper and discharged directly against the heated air escaping from the stove, causing a turning back of this heated air.

This construction of damper is particularly effective for use in brooder stoves as the

damper must be actuated by a thermostatic element and thus must be delicately poised.

Furthermore, means must be used for checking the fire which acts quickly in order to prevent too great a heat from being generated which would injure the chicks and my damper is particularly designed to secure this effect.

While I do not wish to limit myself to this, I preferably place a false wall 37 in the damper chamber spaced from the wall 11 thereof as the heat, were such a false wall not used, would have a tendency to ignite the coal within the magazine and also some heat would be lost that would radiate from wall 11. Thus preferably I use a double wall formed of the walls 37 and 11 with an air space between. I do not wish to be limited either to the use of the damper chamber as being formed integral with the body of the stove 10, as this damper chamber might be an independent unit.

I claim:—

1. In a brooder stove having a damper opening, a check draft damper mounted in said opening comprising a relatively flat body portion and an inwardly extending angular portion at the upper end of the damper, the damper being pivoted for swinging movement at the junction of these two portions, the margins of the opening being formed to provide an inwardly facing seat for the lower margin of the damper, and an outwardly facing seat for the upper margin of the damper, and means to swing the damper inward and upward to open the check draft.

2. In a brooder stove having a check draft opening, a check draft damper disposed in said opening consisting of a relatively flat portion having an angularly related portion at its upper end, the angularly related portion extending inward and upward and increasing in thickness toward its inner end whereby it may act as a counterbalancing weight, the damper being pivotally mounted upon the wall of the opening on an axis approximately coincident with the junction between the two portions of the damper, the wall of the opening being formed to provide an inwardly facing seat for the lower portion of the damper below the pivot thereof and an outwardly facing seat for the angular end portion of the damper, and means for operating the damper.

3. In a brooder stove having a check draft opening, a check draft damper disposed in said opening consisting of a relatively flat portion having an angularly related portion at its upper end, the angularly related portion extending inward and upward and increasing in thickness toward its inner end whereby it may act as a counterbalancing weight, the damper being pivotally mounted upon the wall of the opening on an axis approximately coincident with the junction be-

tween the two portions of the damper, the wall of the opening being formed to provide an inwardly facing seat for the lower portion of the damper below the pivot thereof and an outwardly facing seat for the angular end portion of the damper and means for operating the damper including an ear projecting outward from the damper just below the pivot thereof and an operating rod operatively engaged with said ear.

10 4. In a brooder stove having a smoke flue and a check draft opening disposed within the flue at the base thereof, a damper pivoted adjacent its upper end in said opening so that the lower end of the damper will swing inward and upward across a substantial area of the lower portion of the flue.

15 5. In a brooder stove having a check draft opening and having a flue above the check draft opening, a damper pivoted adjacent its upper end in said opening, the greatest portion of the weight of the damper being inward of its pivotal point whereby the damper will close by gravity, said damper when 20 raised, swinging inward and upward and across a substantial portion of the opening of 25 the flue.

20 6. A brooder stove having a check draft opening and having a flue, a damper pivoted adjacent its upper end in said opening, the damper having an angularly extending portion forming an acute angle with the body 25 of the damper, and normally bearing against the upper wall of the flue opening, the body 30 of the damper and said extension thus acting to urge the damper to a closed position, 35 said extension when the damper is raised a predetermined distance from its seat moving out of contact with the upper wall of the 40 damper opening to thereby permit the inlet of air both above and below the body of the 45 damper, said extension acting as a counter-balance to the additional leverage exerted by the damper as it moves toward a horizontal position.

45 In testimony whereof I hereunto affix my signature.

ROSCO O. PENCE.
